STOP BLOCK

Thomas H. Edelblute, Reynoldsville, Pa., assignor to Campbell Chain Company, York, Pa., a corporation of Pennsylvania

Application January 19, 1950, Serial No. 7,319

Term of patent 14 years

(Cl. D54—11)

To all whom it may concern:

Be it known that I, Thomas H. Edelblute, a citizen of the United States, residing at Reynoldsville, in the county of Jefferson and State of Pennsylvania, have invented a new, original, and ornamental Design for Stop Blocks, of which the following is a specification, reference being had to the accompanying drawing, forming part thereof.

Fig. 1 is a front elevation of the stop block, showing my new design; Fig. 2 is a side elevation thereof; and Fig. 3 is a plan view thereof.

I claim:

The ornamental design for a stop block, substantially as shown.

THOMAS H. EDELBLUTE.
